(57) CLAIM

The ornamental design for a bench, as shown and described.

DESCRIPTION

FIG. 1 is a front perspective view of a bench according to the present invention.

FIG. 2 is a front elevation view of the bench illustrated in FIG. 1.

FIG. 3 is a rear elevation view of the bench illustrated in FIG. 1.

FIG. 4 is a side elevation view of the bench illustrated in FIG. 1.

FIG. 5 is another side elevation view of the bench illustrated in FIG. 1.

FIG. 6 is a top plan view of the bench illustrated in FIG. 1.

FIG. 7 is a bottom plan view of the bench illustrated in FIG. 1.

FIG. 8 is a perspective view of another embodiment of the bench illustrated in FIG. 1 according to the present invention.

FIG. 9 is a front elevation view of the bench illustrated in FIG. 8.

FIG. 10 is a rear elevation view of the bench illustrated in FIG. 8.

FIG. 11 is a side elevation view of the bench illustrated in FIG. 8.

FIG. 12 is another side elevation view of the bench illustrated in FIG. 8.

FIG. 13 is a top plan view of the bench illustrated in FIG. 8.

FIG. 14 is a bottom plan view of the bench illustrated in FIG. 8.

FIG. 15 is a front perspective view of another embodiment of the bench illustrated in FIG. 1 according to the present invention.

FIG. 16 is a front elevation view of the bench illustrated in FIG. 15.

FIG. 17 is a rear elevation view of the bench illustrated in FIG. 15.

FIG. 18 is a side elevation view of the bench illustrated in FIG. 15.

FIG. 19 is another side elevation view of the bench illustrated in FIG. 15.

FIG. 20 is a top plan view of the bench illustrated in FIG. 15; and,

FIG. 21 is a bottom plan view of the bench illustrated in FIG. 15.

The broken lines depict elements of bench that form no part of the claimed design.

1 Claim, 12 Drawing Sheets
